INDOOR FOOTBALL GAME

Edward T. Arnn, Colorado Springs, Colo.

Application August 13, 1948, Serial No. 44,001

4 Claims. (Cl. 273—94)

1

This invention is a simulated football game, in which the standard rules of football are followed fairly closely, and the actual moves made on the game board made to parallel actual plays of the football field as far as possible.

The game of this invention comprises a game board, laid out like a football field, with goal posts, side lines, yardage lines and the like.

There are eleven game pieces for each team, the pieces for each team being distinctively colored. In each set of game pieces, there would be the usual five linemen, two ends and four backs.

Each game piece is shaped to actually carry a small disk or the like simulating the football. Each game piece, representing a particular player, is provided with a shallow recess in its top within which a small disk, representing the football, rests. The "ball" travels along with the game piece, such travel indicating the actual travel of the ball on the field. The game pieces or "players" are propelled or "flipped" by the fingers of the persons playing the game. The movements of the players are therefore controlled manually, and so the game is a game of skill, rather than a game of chance.

While the "ball" normally travels or rides along on top of its game piece as just mentioned, it can be displaced therefrom by a sufficient impact. Such impact and displacing or loss of the ball may result from contact with an opposing game piece, signifying a tackle. However, if the ball thus displaced comes to rest against another game piece or "player," it is considered to be a fumble, that is recovered by that player.

Such displacing impact may also result from too sharp a blow from the finger of the person "flipping" the game piece on which the "ball" is riding.

The game also comprises five and ten yard markers or scribes, for defining zones about a ball about to be put in play in a scrimmage, within which zones opposing players must be located in order to be eligible to tackle the "player" carrying the "ball." Measurements are made from the center of one game piece to the center of another.

Further details of the game will be described in connection with the accompanying drawings, wherein:

Fig. 1 is a plan view of the game board.

Figs. 2 and 3 are edge and plan views of game pieces representing the linemen.

Figs. 4 and 5 are edge and plan views of game pieces representing the ends.

Figs. 6 and 7 are edge and plan views of game pieces representing the backs.

2

Figs. 8 and 9 are edge and plan views of the element used to represent the football.

Figs. 10 and 11 are edge and plan views showing the ball in place on a game piece representing a player.

Fig. 12 shows zones about a runner traveling in a given direction within which opposing players are eligible to tackle the runner.

Fig. 13 shows a marker or scribe of a type for marking three, five and ten yard zones.

Fig. 14 shows a typical line-up for a scrimmage.

The game board of Fig. 1 is preferably a flat piece 2 of any suitable material of any convenient size, say about 4½ by 9 feet, which may be hinged to fold in the middle, or in convenient lengths for storage, etc. It is provided with the usual goal posts, end zones and yardage lines, as on a standard football field. An upstanding rim or border 4 may surround the field at its sides and edges.

20 The game pieces representing the players are preferably disks 6, provided with shallow recesses 8, on one or both sides, the edges of the recesses extending upwardly and outwardly in a curve or bevel 10, the sides 12 of the recesses preferably

25 being at an angle of about 30° to 60° to the horizontal, for reasons discussed below. The center of each recess 8 contains a notch 9 for use with the marker or scribe to be used in defining the zone about the "ball carrier" as described below.

30 Five game pieces 6 are provided for the five linemen, that is, for the center, guards and tackles. These five pieces representing the linemen are preferably of the same color, and each could be further distinctively labeled to indicate his precise position in the line.

35 Two more game pieces 6a, Figs. 4 and 5, are provided, for the two ends, colored to differentiate from the others, and preferably labeled "End."

Four more game pieces 6b, Figs. 6 and 7, are provided for the four backs, colored differently from the others and preferably labeled to designate particular backs.

Structurally, all the game pieces of Figs. 4-7 are preferably similar to the game pieces of Figs. 2 and 3.

45 The "ball" is represented by a disk 14, about twice as thick as the depth of one of the recesses 8, although, of course, its size may be varied. The edges of the disk 14 are rounded or beveled, as shown at 15. The diameter of disk 14 is such that the disk 14 rests in a recess 8 in any of the disks representing the players, as in Fig. 10; when in this position the "ball" 14 is in the possession of the player represented by the disk and movements of this player represent movements of the ball. The center of the disk representing the

50 55

"ball" is notched as at 16 for the purpose of measuring zones about the "ball carrier" as described below.

An important feature of the game is that the shape and weight of the ball 14, considered in connection with the depth of the carrying recesses 8 and the angle of the sloping sides 12, all cooperate so that when the player 6, or 6a or 6b, carrying the ball, is subjected to a slight push or light impact, the player and ball move along together, the progress of such player representing the progress of the ball. However, where the ball carrying player 6 is subjected to a sharp impact, as by too sharp a flip or blow with the finger or too sharp a contact with another player, the ball rides up the inclined sides 12 of recesses 8 and drops off the disk 6 and the ball is considered as lost by that player.

A play is initiated by a person "flipping" or snapping with his finger a disk carrying the ball, as in Fig. 10. His opponent then "flips" or snaps one of his players, to try to dislodge the ball from the opposing player; if he does dislodge the ball, this is considered a tackle. However, if the ball so dislodged comes to rest against a player of either side, this is regarded as a fumble, which is regarded as recovered by that player.

A typical line-up for a scrimmage is shown in Fig. 14.

A marker, scribe or caliper 29 as shown in Fig. 13, of a length to represent ten yards, is used to define a zone 17, as shown in Fig. 12, on that side of the ball 14 toward which it is being advanced. A second marker or scribe, of the type shown at 20 in Fig. 13, is used to define a zone 18, on the other side of the ball. Opposing players 6 within zones 17 and 18 are considered as eligible to "tackle" the player carrying the ball, players outside these zones being ineligible to tackle.

Further details of the game and method of play appear from the following rules of play:

1. The rules of football apply to this game in as much as is possible.
2. The methods of running, passing, and kicking the ball and of blocking, running interference, and tackling are roughly the same as in real football.

A. To run the ball

The ball is placed in the recess of the man 6 who is to run the ball and the man flipped with the index finger, for as much gain as possible. The runner does not necessarily have to be flipped for a gain; he may be flipped in any direction desired.

Care must be taken not to flip the runner so hard that the ball becomes dislodged from the runner. If it does then the man is considered down at the spot from which he was flipped. This would correspond to the runner in a real football game tripping and falling. This would naturally constitute a down. The ball and men are so made that an attempt to flip the runner for too great a gain results in the ball becoming dislodged and thereby preventing the offensive team from making a touchdown almost every time they have the ball.

B. To tackle

To tackle, the defensive player flips one of his men in such a way as to cause that man to strike the runner (the term runner as used herein is synonymous with that of ball carrier) dislodging the ball completely from the runner. This

constitutes the tackle and must not be confused with a fumble. Dislodging the ball completely from the runner is the method of tackling in this game. However, if in the process of tackling the runner the ball rolls off and comes to rest in direct contact with any other player of either team then it is considered as a fumbled ball which has been recovered.

The tackle must be made directly by the defensive team. The defensive player may not at any time flip one of his men causing that man to strike one of the offensive team's men so as to make the offensive team's own man tackle his runner. If this happens then the ball is replaced on the runner in his original position and the play resumed until the runner is legally tackled. The illegal tackle does not constitute a down.

The runner, when legally tackled, is considered down at the very spot on which he stood when tackled and not at the spot where the ball or the runner lands after the impact of the tackle. This rule may be varied to suit the players.

Except on the kickoff and the return of a punt 25 no man may be used to tackle the runner who is further away than a "ten yard" radius in front or to the front sides of the runner, nor may a man who is more than a "five-yard" radius distance from the rear or rear sides of a runner be used 30 to tackle the runner (Fig. 12). Apparatus like Fig. 13 is included with this game to measure these distances. This rule is optional or may be varied to suit the players.

35

C. To block

To block or "run interference" the offensive player flips one of his men in such a way as to interpose his man between a prospective tackler and the runner thus preventing, if successful, the prospective tackler from making a legal tackle as discussed in "B" above. Also the offensive player may block by flipping one of his men in such a way as to drive a prospective tackler further away than the legal tackling range about the runner (see B above) or by driving the prospective tackler out of the playing field whence that man and his blocker, if he goes out of bounds also, cannot be used for the rest of the play. A blocker may block out more than one man if desired or possible. He may even be used to block out one of his own men. No man may be used (flipped) two times in succession for blocking; see below. A "blocker" must be within a 10-yard 50 radius in front or 5-yard radius behind of the man he is to block to be eligible to block out this man. This rule is optional, or the distances may be varied to suit the players.

60

D. To pass

After the defensive team has had its one chance to tackle the passer (see Rule 5) then the ball is placed on the field at the spot where the passer stood and the passer moved back "ten yards" from the ball in line with the direction in which he intends to pass the ball and then the passer is flipped so as to strike the ball driving it towards the receiver. In order for the pass to be completed the ball must strike the receiver. It is incomplete if it fails to touch the receiver. If more than one of the men are touched by the ball then the last man touched receives the ball. If the only man or the last man touched by the ball is 65 one of the defensive team's men then the pass is

considered to be intercepted. The ball itself is never flipped.

E. To kick

The same procedure for passing the ball is used in kicking the ball, the kicker being placed only "five yards" behind the ball instead of "ten" as in passing. In kicking the ball on the kickoff or for a punt the last man touched by the ball either receives it or downs it according to the rules of football. When it fails to touch a man and is still on the playing field then the nearest man to the ball picks it up or downs it. If the ball goes into the end zone or out of bounds then the regular rules of football are used to put the ball back into play.

For extra points after a touchdown or for a field goal the ball must be kicked between the circles or other device representing the goal posts.

The ball is never flipped in kicking or in passing.

F. Centering

The ball is placed on the center until the play is ready to begin then it is passed, by hand, back to the man who is to carry the ball. The ball may not be centered back further than "fifteen yards" or further to the sides of the center than "three yards." This zone is shown at 22 in Fig. 14.

G. Miscellaneous

Trick plays, these are rather difficult to make practical for this particular game. The players may work out their own trick plays.

3. Regular football line-ups are used in this game.

4. *The kickoff.*—After the kickoff and one of the receiving team's men has received the ball that team first is allowed two blocks (blocks or interference being used whichever is desired) the same man not being used twice in succession. Next the defensive team is allowed one chance to tackle the runner, the rule that the tackler must be within a "ten yard" radius in front of the runner or a "three yard" radius behind the runner not applying to the kickoff or the return of a punt. If this first attempt to tackle the runner is unsuccessful then the runner is flipped in any direction desired preferably for as much gain as possible. Following this the offensive team has two chances to block out prospective tacklers or use interference. Then the defensive team has one more chance to tackle the runner and so on in the sequence just described until a touchdown has been made or the runner is tackled or struck so as to be forced out of bounds.

5. *Line plays.*—Standard lineups are used, the offensive team lining up first. To start a play the ball is centered back to the man who is to carry the ball by simply removing the ball from the center and placing it on the man who is to carry the ball. The offensive team starts the play by taking its allotted two blocks in order to open up a hole in the defensive line, or to send out a man to receive a pass, or to clear the way for a punt, etc. Next, the defensive team has one chance to tackle the man with the ball or if that is impossible it may use this chance to block up the hole made in its line. In attempting to do the latter the defensive man may be flipped in such a way as to drive one or more of his own teammates into the opening made in his team's line. After this the offensive team may run, pass, or kick the ball. After an attempt to run or pass the ball, if successful, the offensive team then has two more chances to block. Next the defensive

team has its one opportunity to tackle the man with the ball. If this is unsuccessful then the runner is flipped for as much gain as possible and then two blocks "thrown" by the offensive team. Then the defensive team has another chance to tackle the runner and so on in the sequence given until a touchdown is made or the runner tackled. For every "ten yards" gained a first down is earned. If in four downs the offensive team fails to gain the necessary "ten yards" for a first down then the ball goes over to the defensive team on downs.

6. If one player is found off side after the play has started the offending team may be penalized for off side. If one man lands on top of another the top man's team is penalized for holding.

7. If at any time after a tackle or a fall (see Rule 2-A) the ball is found touching a man then it is considered as a fumble recovered by the team whose man the ball is touching.

8. The game is timed just as the real game is in as far as is practical. An alarm clock may be used to time the quarters. If a referee is present a penalty may be imposed for taking too much time initiating a play, or for delaying the game.

9. No man may be moved without flipping him according to the rules given above. Exceptions being in lining up the men and in moving a passer or kicker back from the ball.

30. 10. By use of the imagination almost anything that occurs in a real football game may be duplicated in this game.

For those not familiar with the rules of football a book of rules should be purchased.

35. While the invention and rules of play have been described in some detail, it should be understood that the invention is not to be limited to this precise disclosure, but may be carried out in other ways.

40. I claim as my invention:

1. In a simulated football game, a game piece representing a player and comprising a disk provided with an annular shallow generally flat-bottomed recess adapted to receive a simulated football, with an annular upstanding rim adapted to retain said simulated football, with an annular incline extending upwardly and outwardly from the outer portion of said recess to the inner portion of said rim and being adapted to cause the simulated football to be dislodged by a sharp horizontal movement of the piece, and further provided with a central hole adapted to receive one point of a measuring device whereby pieces may be accurately positioned on the playing surface and properly spaced from one another.

45. 2. In a simulated football game, a game piece representing a player and comprising a disk provided with an annular shallow generally flat-bottomed recess adapted to receive a simulated football, with an annular, upstanding rim adapted to retain the simulated football, with an annular incline extending upwardly and outwardly from the outer portion of said recess to the inner portion of said rim and being adapted to cause the simulated football to be dislodged by a sharp horizontal movement of the piece, and further provided with a central hole adapted to receive one point of a measuring device, and an annular element simulating the football, said element being substantially twice the thickness of the depth of the recess and being provided with rounded edges adapted to mate with the annular incline of said disk and being provided with a

50. 65. 70. 75. central hole adapted to receive a point of a meas-

uring device whereby pieces may be accurately positioned on the playing surface and properly spaced from one another.

3. In a simulated football game, a game piece representing a player and comprising a disk provided at each side with an annular shallow generally flat-bottomed recess adapted to receive a simulated football, with an annular, upstanding rim adapted to retain the simulated football, with an annular incline extending upwardly and outwardly from the outer portion of said recess to the inner portion of said rim and being adapted to cause the simulated football to be dislodged by a sharp horizontal movement of the piece, and a central hole adapted to receive a point of a measuring device whereby pieces may be accurately spaced on the playing surface and properly spaced from one another.

4. In a simulated football game, a game piece representing a player and comprising a disk provided at each side with an annular shallow generally flat-bottomed recess adapted to receive a simulated football, with an annular, upstanding rim adapted to retain the simulated football, with an incline extending upwardly and outwardly from the outer portion of said recess to the inner portion of said rim and being adapted to cause a simulated football to be dislodged by a sharp hori-

zontal movement of the piece, and further provided with a central hole adapted to receive a point of a measuring device, and an annular element simulating the football, said element being substantially twice the thickness of the depth of the recess and being provided with rounded edges adapted to mate with the incline of said disk and being further provided at each side with a central hole adapted to receive a point of a measuring device whereby pieces may be accurately positioned on the playing surface and properly spaced from one another.
